By *James Hutchinson* Attorney:

UNITED STATES PATENT OFFICE.

CHARLES O. PROWSE, OF HOPKINSVILLE, KENTUCKY.

AUTOMATIC FUSE-BLOCK.

No. 913,913.

Specification of Letters Patent.

Patented March 2, 1909.

Application filed September 26, 1907. Serial No. 394,532.

To all whom it may concern:

Be it known that I, CHARLES O. PROWSE, a citizen of the United States, residing at Hopkinsville, in the county of Christian and State of Kentucky, have invented certain new and useful Improvements in Automatic Fuse-Blocks, of which the following is a specification, reference being had therein to the accompanying drawing.

10 This invention relates to an improvement in an automatic fuse block and lightning arrester, and the object of the invention is the provision of a device of this character, particularly adapted for use at subscribers' stations on telephone lines and the like, employing a plurality of fuses and so constructed whereby when the circuit has been broken by an excessive current blowing one of the fuses, said circuit will be automatically and instantaneously restored through another of said fuses.

15 A further object of the invention is the provision in a device of this character, of means for grounding the excessive current after the burning of one of the fuses and before the current is remade through the next successive fuse.

20 A further object of the invention is the provision of a device of this character which will protect both the lead and return wires of the instrument from excessive currents.

25 A further object of the invention is the provision in a device of this character, of means for protecting the instrument from injury from excessive currents which for any reason fail to blow or rupture the fuse.

30 Other objects of the invention will be apparent from the detailed description herein-after when read in connection with the accompanying drawings forming a part hereof, wherein a preferable embodiment of my invention is shown and wherein like characters of reference refer to similar parts in the several views.

35 In the drawings: Figure 1 is a side elevation of one side of my improved automatic fuse block and lightning arrester. Fig. 2 is a similar view, one side of the casing being removed. Fig. 3 is a top plan view, the casing being shown in elevation. Figs. 4, 5 and 6 are detail views, and Fig. 7 is a detail view of a modified form showing the manner of making the line connection with the device.

40 Referring now more particularly to the drawings, A represents a block of substan-

tially rectangular formation, which is formed of any suitable non-conducting material and is adapted to be secured to a wall or other suitable support by brackets of any suitable construction projecting from one edge thereof. The block A is provided on opposite sides and adjacent opposite edges thereof with grooves a, which are preferably T-shaped in cross-section and which extend substantially the full length of said block.

45 B represents a plurality of pivotally supported contact members formed of conducting material, which are arranged in vertical series on both sides of the block A adjacent the grooves a therein. The contact members B are pivoted on suitable studs carried by the block A and interposed between each of said contact members and said block is a spring washer b, which serves to hold the contact member in any position to which it may be moved. The contact members B are each provided with a projecting arm b' which normally occupies a substantially horizontal position and projects for a slight distance into the grooves a in the block A, the projecting end of said arm being provided with a concave contact portion b'', which is preferably tipped with platinum so as to insure a good connection. Rigidly secured to the members B and extending rearwardly therefrom are a plurality of spring arms B', which are formed of conducting material and are provided at the free ends thereof with studs of any suitable construction to permit the attachment of fuses thereto. Secured to opposite faces of block A are a plurality of studs or pins b³, which are positioned adjacent the pivotal points of the contact members B and which serve as stops to limit the downward movement of the spring arms B', said arms being maintained in substantially horizontal positions when in contact with said stops.

50 Block A is provided on the opposite faces thereof and adjacent opposite edges thereof with longitudinally extending channels within which are seated metallic strips C of conducting material, which strips are connected in any suitable manner to the ground. Communicating with the channels in which are seated the metallic strips C are a plurality of horizontally arranged recesses which extend to the edges of the block, there being one such recess provided for each of the contact members B. Removably secured in each horizontally disposed recess are a pair of

- superposed carbon plates D D between which is arranged a layer of mica. The carbon plates are held in position within the recesses by means of leaf springs D' which are secured 5 to the block A, the free ends of said springs engaging the top most one of said carbon plates. Each of the springs D', which are of conducting material is provided at the free end thereof with a stud d'.
- 10 E designates a plurality of fuses, which may be of any suitable construction and which are arranged to be secured in two groups, one on each side of the block A. The intermediate portions of the fuses E are 15 looped about the studs d' carried by the leaf springs D', while the ends of each group of fuses are secured respectively to the studs carried by the spring arms B', and to metal strips F of conducting material secured to 20 the block A, there being two such strips provided, one on each side of the block. From one of the strips F, a wire F' leads to the telephone or other instrument, while to the other strip F is connected the return wire F² leading 25 from the telephone or other instrument. In securing the fuses E to the block, the same are drawn taut so as to draw the spring arms B' into contact with the studs b² and place 30 said arms under tension.
- 30 Secured to the edges of the block A and extending longitudinally thereof are two metal strips of conducting material G, each of which is provided along one edge thereof with a plurality of projections g, said projections being so spaced as to occupy positions intermediate the contact members B pivotally secured to the faces of the block. The strips G are electrically connected by 35 means of a metallic strip G' which is secured 40 to and extends across the top of said block, and one of said strips is connected by a suitable wire G² with the ground.
- 45 Slidably mounted in the T-shaped grooves a formed in the opposite faces of the block A are blocks H and removably secured to the face of each of said blocks is a metal plate h of conducting material. Carried by each of the plates h is an arm h', to which the line wire of the circuit is adapted to be connected; a stud h² which is normally arranged to be seated in the concave portion b² of one of the contact members B and which is preferably tipped with platinum so as to insure a good contact with said contact member; and a spring finger h³ which extends laterally therefrom and is provided with a rearwardly bent portion, the free end of which is adapted to successively contact with the projections g on the plate G adjacent thereto when the block H is 50 shifted in the groove a. Journaled in the base of block A and positioned on opposite sides thereof are a pair of spring actuated winding drums I upon each of which is wound a cord or wire i the free ends of said cords or 55 wires being connected to the blocks H which 60

are slidably mounted in the grooves a formed in the block A. Carried by each of the spring actuated drums I is a gear I' which meshes with a pinion K which is loosely mounted on a stub shaft k carried by the block A. The 70 pinions K are each provided with a pair of separated stops k' k² projecting laterally therefrom and loosely mounted on the stub shaft k so as to swing between said stops is a governor arm K¹, the ends of which are 75 weighted and against which bears a spring K².

The operation of the automatic fuse block and lightning arrester is as follows: The blocks H are normally held at the tops of the grooves a with the platinum tipped studs h² 80 thereof engaging the concave portions of the topmost contact members B. If now, an excessive current should strike the line, it would pass through the arm h', the platinum tipped stud h², the topmost contact member 85 B, the spring arm B', and to the fuse E which would in consequence thereof be ruptured. As soon as the fuse E is ruptured, the topmost member B will be released and will permit the spring actuated drum I to 90 draw the block H downwardly in the groove a until the platinum tipped stud h² seats itself in the concave portion of the next contact member B, when the current will again be restored to the line. Before the stud h² 95 contacts with the next contact member B, however, the spring finger h³ will contact with one of the projections g on the plate G and thereby permit the excessive current on the line to pass to the ground. Should the 100 excessive current still be on the line, when the stud h² contacts with the next contact member B, the fuse connected to said member will be burned out and the operation above described repeated. Immediately one 105 of the fuses is ruptured, the spring actuated drum I will quickly turn whatever distance is permitted by the stops k' and k² projecting from the pinion K and this distance is sufficient to bring the spring finger h³ carried by 110 the block H in contact with one of the projections of the ground plate G. By the time that the block A has traveled this distance, however, the stops k' and k² are moved into engagement with the weighted governor arm 115 K¹ and the rotation of the spring actuated drum is checked so that the block H will be more slowly drawn into engagement with the next contact member B.

It is obvious that the governor mechanism 120 herein described may be dispensed with and the spring actuated drum alone be relied on to actuate the block H.

Frequently currents of such a strength and character as would injure the telephone or 125 other instrument pass over the line without rupturing the fuse and it is to prevent currents of this character from reaching the instrument that I have provided the carbon plates D D heretofore described. When a 130

current of this character passes through one of the fuses without rupturing the same it will jump from the top carbon plate with which the fuse is in electrical connection 5 through the leaf spring D', through the sheet of mica d to the bottom carbon plate and from thence through the metallic plate C, with which the bottom carbon plate is in electrical connection, to the ground. The 10 line wire which is connected to the movable block has sufficient slack therein to permit movement of the block upon the rupture of the fuses.

The block A and the part carried thereby 15 are preferably housed or inclosed by a casing a' which is formed in two sections, provided with suitable apertures which are designed to be engaged by bolts projecting from the block said sections being secured on said 20 block by thumb nuts engaging the projecting ends of said bolt. Each of the sections of the casing is provided with a longitudinal slot therein and marked on each section adjacent said slot are figures corresponding to 25 the number of fuses on the block. Each of the sliding blocks H' carries a pointer which projects through the slot before referred to and coöperates with the numbers on the casing section to indicate the condition of the 30 fuses on the block.

In Fig. 7 of the drawing, I have shown a modified method of connecting the line wires of the circuit to the block. In this form of my invention, the sliding blocks H are made 35 of conducting material as are also the cables or cords i which connect the same with the spring actuated drums I, and said cables are connected with contact plates I² carried by the drums I and extending to the axles 40 thereof. The axles of the drums I in this form of my invention project without the casing and have threaded thereon binding screws i² which constitute the means of attachment for the line wires of the circuit.

45 While I have described the block as equipped with two sets of fuses, so as to protect both the lead and return wires to and from the instrument, it is obvious that where only one wire is used and the ground 50 is utilized as the return, only one side of the block need be so equipped.

I do not desire to limit myself to the precise form and construction shown in the drawings, as it is obvious that many minor 55 changes might be made thereto without departing from the spirit of the invention as defined in the appended claims.

Having thus described the invention, what is claimed is:—

60 1. In a device of the character described, a block, a plurality of fusible strips carried by said block and adapted to be connected to one line of an electric circuit, a movable contact member adapted to be connected to the 65 other line of said circuit and adapted to suc-

cessively make connection through the fusible strips, and a ground plate positioned on said block and provided with a plurality of contact portions adapted to be engaged by said movable contact member during the movement thereof, said contact portions being arranged intermediate said fusible strips. 70

2. In a device of the character described, a block, a plurality of movable contact members secured thereto, a metal plate secured to 75 said block, a plurality of fuses connecting said movable contact members and said metal plate and serving to hold said contact members normally against movement, a contact member slidably secured to said block and adapted to successively engage 80 said movable contact members, and a plurality of ground contacts carried by said block intermediate said movable contact members and adapted to be successively engaged by said slidable contact member during its travel from one to another of said movable contact members. 85

3. In a device of the character described, a block provided with a groove therein, a plurality of contact members pivoted to said block and provided with portions adapted to normally overlie the groove therein, a plurality of fuses connected to said contact members and serving to hold the same in 90 their normal position, a contact member slidably mounted in the groove in said block and adapted to coöperate with said pivoted contact members, a motor actuated drum carried by said block, and a cable connecting 95 said motor actuated drum and said slidably mounted contact member. 100

4. In a device of the character described, a block, a plurality of movable contact members secured thereto, a plurality of fuses connected to said contact members and serving to normally hold the same against movement, a contact member slidably secured to said block and adapted to successively engage 105 said movable contact members, a motor actuated drum carried by said block, and a cable connecting said drum and said slidably mounted contact member. 110

5. In a device of the character described, a block, a plurality of movable contact members secured thereto, a plurality of fuses connected to said contact members and serving to normally hold the same against movement, a contact member slidably secured to 115 said block and adapted to successively engage said movable contact members, a motor actuated drum carried by said block, a cable connecting said drum and said slidably mounted contact member, and a governor for said motor actuated drum. 120

6. In a device of the character described, a block, a plurality of movable contact members secured thereto, a plurality of fuses connected to said contact members and serving to normally hold the same against move- 125 130

- ment, a contact member slidably secured to said block and adapted to successively engage said movable contact members, a plurality of ground contacts carried by said block and adapted to be successively engaged by said slidable contact member, a motor actuated drum, and a cable connecting said motor actuated drum and said slidably mounted contact member.
- 10 7. In a device of the character described, a block, a plurality of movable contact members secured thereto, a metal plate secured to said block, a plurality of fuses connecting said movable contact members and said metal plate and serving to hold said contact members normally against movement, a ground plate carried by said block and provided with a plurality of contact portions arranged intermediate the movable contact members, and a movable contact block arranged to successively engage said movable contact members and the contact portions of said ground plate.
- 25 8. In a device of the character described, a block, a plurality of spring arms pivoted to said block and provided at their forward ends with contact portions, a plurality of pins carried by said block and arranged to support the opposite ends of said spring arms, a plurality of fuses carried by the block and engaging said spring arms, and a movable contact member arranged to successively engage the contact portions of said spring arms.
- 30 9. In a device of the character described, a block, a carbon plate carried thereby and provided with a ground connection, a second carbon plate seated upon said first men-

tioned plate, a metal spring secured to the block and overlying the upper carbon plate, ⁴⁰ said spring being provided with a stud, and a fuse looped about the said stud and having its ends adapted for connection with the line wires of a circuit.

10. In a device of the character described, ⁴⁵ a block, a plurality of spring arms pivoted to said block and provided at their forward ends with contact portions, means carried by the block for supporting the rear ends of said spring arms, a plate carried by the ⁵⁰ block and adapted to be connected to one of the line wires of an electric circuit, a plurality of taut fuses connecting said plate and the rear ends of said spring arms, and a movable contact member arranged to successively engage the contact portions of ⁵⁵ said spring arms.

11. In a device of the character described, a block, a spring arm pivoted to said block and provided at its forward end with a contact portion, means carried by the block for supporting the rear end of the spring arm, a contact member carried by the block, a taut fuse interposed between said contact member and the rear end of said spring arm, a ⁶⁰ broken ground connection extending from the fuse, and a movable contact member adapted to coöperate with the contact portion at the forward end of the spring arm.

In testimony whereof I affix my signature ⁷⁰ in presence of two witnesses.

CHARLES O. PROWSE.
